[57] **CLAIM**

The ornamental design for a modular electronic equipment case, as shown and described.

DESCRIPTION

FIG. 1 is a perspective view showing the left side, front and a portion of the top of the modular electronic equipment case showing my new design;

FIG. 2 is a right side view which is a mirror image of

the left side of the modular electronic equipment case;

FIG. 3 is a front elevational view;

FIG. 4 is a rear elevational view;

FIG. 5 is a top plan view;

FIG. 6 is a bottom plan view; and

FIG. 7 is a perspective view of a second embodiment of my design.
